United States Patent Office.

HERMAN VASSEUR, OF WALLINGFORD, CONNECTICUT, ASSIGNOR TO SIMPSON, HALL, MILLER & CO., OF SAME PLACE.

Design No. 4,440, dated October 25, 1870.

DESIGN FOR A FRUIT-STAND.

The Schedule referred to in these Letters Patent and making part of the same.

To all whom it may concern :

Be it known that I, HERMAN VASSEUR, of Wallingford, in the county of New Haven and State of Connecticut, have invented a new Design for Fruit-Stand; and I do hereby declare the following, when taken in connection with the accompanying photographic illustration, to be a full, clear, and exact description of the same, and which said illustration constitutes a part of this specification, and represents a perspective view.

This invention relates to a design for stand for holding fruit, and consists in the peculiar configuration and ornamentation of the same.

Upon a base a pillar is formed representing three female figures supporting above them the basin or plate for the reception of the fruit, the said basin being of the configuration fully shown in the accompanying photographic illustration.

I claim as my invention—

The design for fruit-stand, as shown and described.

H. VASSEUR.
